[57] CLAIM

The ornamental design for a stork sign, as shown.

DESCRIPTION

FIG. 1 is a front elevational view of a stork sign showing my new design.

FIG. 2 is a side elevational view thereof.

FIG. 3 is a bottom view thereof.

FIG. 4 is a rear elevational view thereof.

FIG. 5 is an elevational view of the side opposite to that shown in FIG. 2 thereof.

FIG. 6 is a top view thereof.
